GAS VALVE ASSEMBLY FOR OIL WELLS

Leonard O. Wharton, Jr., Fort Worth, Tex.

Application June 20, 1949, Serial No. 100,173

3 Claims. (Cl. 166—2)

1

This invention relates to the production of oil from beneath the earth's surface, and has reference to the use of gas pressure for raising or assisting in raising oil in the tubing of an oil well.

An object of the invention is to maintain gas pressure within the well casing, as required in many states for conserving natural gas. Maintaining the gas pressure within the casing also prevents the "coning" of salt water in production areas where salt water lies beneath the oil. If the gas pressure were not controlled, the velocity of the gas entering the lower end of the well bore would not only lift part of the oil, but would raise or "cone" the salt water into the well bore or casing.

Another object of the invention is to provide a dependable and positive acting apparatus for regulating and automatically controlling the entry of gas from within the well casing or well bore into the well tubing for raising or assisting the raising of oil therein. It is to be understood that the present invention may be employed for flowing wells where the gas pressure is adequate, or may be used in conjunction with pumping a well when the gas pressure is insufficient for raising the oil to the earth's surface.

These and other objects will become apparent from the following description and the accompanying drawing, wherein:

Figure 1 is a vertical sectional view of an oil well and showing an embodiment of the invention installed therein.

Figure 2 is a vertical sectional view of a flow pipe and valve, together with means for operating said valve.

Figure 3 is an elevation of Figure 2.

Figure 4 is a transverse sectional view taken on line 4—4 of Figure 2.

Figure 5 is an enlarged perspective view of the valve mechanism illustrated in Figures 2 and 4.

Figure 6 is a transverse sectional view, similar to Figure 4, but illustrating a different type of valve.

Figure 7 is a vertical sectional view of the valve illustrated in Figure 6.

The numeral 10 indicates a well casing extending beneath the earth's surface and above the oil bearing formation. Within the casing 10 there is a string of tubing 11 extending to the earth's surface where the usual casing head assembly (not shown) controls the outlet of oil from the said tubing, and additionally retains gas under pressure within the casing. The static level of the oil 12, as shown in Figure 1, 55

2

seeks a level depending upon the amount of oil in the formation and the gas pressure therein. The lengths of tubing are joined by means of collars 13, and the lower end of the tubing 11 is provided with a perforated pipe or screen 14 for allowing oil to enter said tubing.

One of the collars 13 above the perforated pipe 14 is provided with an integral lateral projection 15 for securing the upper end of a standpipe 16. 10 It will be noted in Figure 1 that there is a vent hole 17 in the standpipe 16 near the upper end thereof.

Referring now to Figures 1 through 5, a flow pipe 18 is connected within the string of tubing 11 above the perforated pipe 14 and below the collar 13 having the lateral projection 15. The flow pipe 18 is constricted near its center and has a relatively small passage 19 therethrough. A rotatable valve element 20 having a transverse port 21 therethrough is arranged for opening and closing the restricted passage 19. Bosses 22 at the upper and lower ends of the flow pipe 18 receive screws 23 which, in turn, secure a diaphragm housing 24 opposite and parallel with the length of said flow pipe 18. As shown in Figures 2, 3 and 4, the diaphragm housing 24 is provided with threads 25 at its upper end for receiving and securing the lower end of the standpipe 16. The diaphragm housing 24 is provided with a diaphragm 26 opposite the flow pipe 18, and which diaphragm is substantially parallel with the length of the latter. The diaphragm 26 covers an opening 27 in the diaphragm housing 24, and in the preferred form of the invention is longer than it is wide so as to provide sufficient area when acted upon by hydraulic pressure to the housing 24, and is secured by means of an elongated ring 28 riveted or otherwise secured in place. A backing plate 30, smaller than the opening 27, is provided on the inner surface of the diaphragm 26; and a reinforcing plate 31, also smaller than the opening 27 is positioned on the outer surface of said diaphragm, the two plates being riveted or otherwise secured together with such rivet means or the like passing through said diaphragm.

On opposing outer surfaces of the flow pipe 18 there are projecting, vertically disposed, ribs 32 which support leaf springs 33 which, in turn, bear against the outer surface of the reinforcing plate 31 and tend to move the diaphragm 26 inwardly into the diaphragm housing 24. Vertical projections 34 on opposite sides of the reinforcing plate 31 are pivotally connected with links 35 which are similarly connected at their opposite

3

ends with cranks 36 secured to opposite ends of the valve element 20.

Referring now to the modified valve arrangement illustrated in Figures 6 and 7, the reinforcing plate 31 is provided at one side with a single projection 37 instead of the vertical ribs 34. The lower end of tubing 11 above the present form of valve is of reduced diameter, as at 38, where it rotatably receives a collar 39. Complementary openings 40 and 41 are respectively provided in the tubing 11 and the collar 39 for registering with each other. A projection 42 on one side of the collar 39 is pivotally connected with one end of a link 43, the opposite end of which is similarly connected with the previously described projection 37 on the reinforcing plate 31. A threaded collar 44 is secured on the lower end of tubing 11 having the reduced diameter 38, retains the rotatable collar 39 in its described position, and a bull plug 45 closes the end of said tubing.

The operation of the first described form of the invention includes positioning the flow pipe 18 beneath the lowest normal static level of the oil 12 in the casing 10, after first substantially filling the standpipe 16 with oil or other liquid. As the oil within the casing 10 rises, the pressure thereof moves the diaphragm 26 inwardly and, by reason of described linkage 35 and 36, communicates the port 21 of the valve element 20 with the constricted passage 19. The gas pressure within the casing 10 and well formation then forces the oil upwardly into the upper string of tubing 11. When the static level of the oil 12 in the casing 10 falls, the weight of the liquid within the standpipe 16 overcomes the pressure of the spring 33 and moves the diaphragm 26 outwardly. The outward movement of the diaphragm 26 turns the valve element 20, and thereby causes the port 21 to be closed.

The operation of the form of the invention illustrated in Figures 6 and 7 is substantially the same as described in the foregoing except that the collar 39 is partially rotated when the diaphragm 26 is moved inwardly causing the ports 41 in said collar to register with ports 40 and thereby providing for the entry of oil into the tubing 11. When the static level of the oil 12 falls, the pressure within the standpipe 16 moves the diaphragm 26 outwardly, and thus closes the ports 40 in the tubing 11.

The described forms of the invention may be made in many ways within the scope of the appended claims.

What is claimed is:

1. A valve assembly for operation beneath the lowermost static level of oil in a well having a string of tubing therein, said assembly comprising: a flow pipe adapted to be connected with said string of tubing and including a passage therethrough communicating said tubing above said flow pipe with said oil, a rotatable valve element mounted in said flow pipe and positioned across passage for opening and closing the same, an elongated housing positioned substantially parallel with and spaced from one side of said flow pipe, means rigidly securing said housing to said flow pipe, a vertical standpipe connected with said housing, said standpipe including an

4

opening through its upper end, a diaphragm assembly mounted in an opening in the side of said housing adjacent said flow pipe, means between said diaphragm and the last said opening providing a fluid excluding seal therebetween, at least one link connecting said diaphragm with said valve element, and means pressing the diaphragm assembly inwardly of said housing for displacing a part of the volume within said standpipe.

2. A valve assembly for operation beneath the lowermost static level of oil in a well having a string of tubing therein, said assembly comprising: a flow pipe adapted to be connected with said string of tubing and having a choke passage formed in and through its axial center, a rotatable valve element mounted in said flow pipe and transversely positioned across said choke passage and extending on opposite sides of said flow pipe, cranks secured to the outer ends of said valve element, a housing positioned substantially parallel with and spaced from one side of said flow pipe, means rigidly securing said housing to said flow pipe, a vertical standpipe connected with said housing, said standpipe including an opening through the upper end thereof, a diaphragm mounted in an opening in the side of said housing adjacent said flow pipe, means between said diaphragm and the last said opening providing a fluid excluding seal therebetween, parallel links connecting the outer surface of said diaphragm with said cranks, and means pressing the diaphragm assembly inwardly of said housing for displacing a part of the volume within said standpipe.

3. A valve assembly for operation beneath the lowermost static level of oil in a well having a string of tubing therein, said assembly comprising: a flow pipe adapted to be connected with said string of tubing and having a choke passage therethrough, a rotatable valve element supported by said flow pipe and transversely positioned across said choke passage and extending outwardly of at least one side of said flow pipe, a crank secured to said extending end of said valve element, a housing positioned substantially parallel with and spaced from one side of said flow pipe, means rigidly securing said housing to said flow pipe, a vertical standpipe connected with said housing, said standpipe including an opening in the upper end thereof, a diaphragm mounted in an opening in the side of said housing adjacent said flow pipe, means between said diaphragm and the last said opening providing a fluid excluding seal therebetween, a link connecting the outer surface of said diaphragm assembly with said crank, and means pressing the diaphragm assembly inwardly of said housing for displacing a part of the volume within said standpipe.
